UNITED STATES PATENT OFFICE

EVERETT E. EPLING, OF ARKANSAS CITY, KANSAS

BUTTER WRAPPING MACHINE

Application filed December 16, 1929. Serial No. 414,438.

The device forming the subject matter of this application is used for wrapping a piece of paper or equivalent material about a cake of any desired kind, such as an oblong, rectangular piece of butter. One object of the invention is to provide novel means for carrying the piece of butter into the machine for wrapping, and out of the machine, after wrapping. Other objects are to provide novel means for placing the paper about the piece of butter, to provide novel means for folding the paper into flaps at the ends of the piece of butter, and to construct a machine in which the various operations incident to the wrapping of a piece of butter, will be carried out in proper synchronism.

It is within the province of the disclosure to improve generally and to enhance the utility of devices of that sort to which the present invention appertains.

With the foregoing and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:

Figure 1 shows in side elevation, a butter wrapping machine constructed in accordance with the invention, the view depicting the side of the machine from which the butter emerges and along which the butter proceeds, after it has been wrapped in paper;

Figure 2 is a top plan of the machine disclosed in Figure 1, parts being broken away;

Figure 3 is an elevation showing the opposite side of the machine from that delineated in Figure 1, parts being broken away;

Figure 4 is a vertical longitudinal section on the line 4—4 of Figure 2;

Figure 5 is a horizontal section on the line 5—5 of Figure 1;

Figure 6 is a transverse section on the line 6—6 of Figure 1;

Figure 7 is a transverse section on the line 7—7 of Figure 1;

Figure 8 is a transverse section on the line 8—8 of Figure 1;

Figure 9 is a vertical sectional view showing certain parts as they will appear after the ram has carried the piece of butter down into the rotor and formed the wrapping paper into U-shape about the butter;

Figure 10 is a view similar to Figure 9, the parts being shown as they will appear after one of the rollers has moved to the left to effect a partial folding of the paper on the piece of butter;

Figure 11 is a perspective view in which the piece of butter and the paper wrapper are shown as they will appear after the machine has done the amount of wrapping indicated in Figure 10;

Figure 12 is a view similar to Figure 10, but showing the parts as they will appear after the rollers have moved up at the end of the piece of butter to make one of the flaps in the paper wrapper;

Figure 13 is a perspective view in which the piece of butter and the paper wrapper are shown as they will appear after the machine has done the amount of wrapping indicated in Figure 12;

Figure 14 is a sectional view made after the manner of Figure 12, but showing the parts of the machine as they will appear after the second flap has been formed at the end of the piece of butter;

Figure 15 is a perspective view in which the piece of butter and the paper wrapper are shown as they will appear after the machine has done the amount of wrapping indicated in Figure 14;

Figure 16 is a view like Figure 14, but showing the parts as they will appear just before the third end flap has been turned down;

Figure 17 is a perspective view of the piece of butter and the wrapping as they will appear after the wrapping operation has proceeded to the point shown in Figure 16;

Figure 18 is a view having the nature of Figure 16, but showing the rotor turned far enough to form the third flap at the end of the chunk of butter;

Figure 19 is a perspective view wherein

the wrapper has been formed into three end flaps on the cake of butter, Figure 19 being supplemental to Figure 18;

Figure 20 is a sectional view illustrating 5 the ejector and other parts which cooperate to form the fourth or final flap which is turned down on each end of the brick of butter;

Figure 21 is a plan disclosing the paper- 10 feeding mechanism, the paper being in place;

Figure 22 is a transverse section of the paper feeding mechanism;

Figure 23 is a diagrammatic end view 15 illustrating, especially, the means whereby the rotor is held releasably to receive the block of butter and the wrapper;

Figure 24 is a composite perspective view 20 illustrating the clutch for the feeding conveyor, the shaft having been omitted;

Figure 25 is a diagrammatic view showing 25 the wrapper as it will appear with respect to the rotor, before the ram has shoved the chunk of butter down into the rotor;

Figure 26 is a view similar to Figure 25, 30 the view illustrating the piece of butter in place in the rotor, the wrapper having been formed into U-shape about the butter, Figure 26 being complementary to Figure 9.

For convenience, in describing the relative locations of parts of the device, that end 35 of the machine to which the letter A is applied in Figure 1 will be referred to as the forward end, the rear end being marked by the letter B.

The machine embodies a frame which, as 40 a whole, is designated by the numeral 1. The frame may be fashioned in various ways, without departing from the spirit of the invention. Those portions of the frame which have significance and importance will receive appropriate designating numerals, as the description proceeds.

General driving mechanism.—An electric motor 2 is mounted on the frame 1 and is located near to the rear end of the frame (Figure 1). A switch 3 is located in any accessible place on the frame 1 and is interposed in the circuit 4 of the motor 2. The shaft 5 of the motor 2 (Figures 4 and 5) extends lengthwise of the frame 1 and into an oil-tight casing 6 disposed transversely of the frame 1 (Figure 8). A worm 7 on the shaft 5 meshes with a worm wheel 8 secured to a transverse main shaft 9 journaled in the frame 1 and extended through the casing 6. The casing 6 is adapted to contain oil for the purpose of lubricating many parts that are inside the casing, as Figure 8 will show. It is from the shaft 9 that the various constituent mechanisms of the machine are driven.

The print feed.—Noting the upper right-hand portion of Figure 4, it will be observed that the prints or blocks of butter are fed into 65 the machine by an endless conveyor 16, and

for the actuation of the print feeding means, a double crank 10 (Figures 7 and 8) is mounted (Figure 8) on one end of the shaft 9. A long, upwardly extended connecting rod 11 is pivoted at its lower end to the crank 10.

A shaft 14 (Figures 3 and 8) extends transversely of the frame 1 and has a rocking movement therein, through an arc of about ninety degrees, a crank arm 12 being secured to one end of the shaft, and the crank arm being pivoted to the upper end of the connecting rod 11. A sleeve 19 (Figures 8 and 24) is rotatable on the intermediate portion of the shaft 14. The sleeve 19 has a sprocket wheel 15 about which is engaged an endless conveyor 16 cooperating with an idle sprocket wheel 17 carried by a shaft 18 which is supported (Figure 2) on one end of the machine.

Reverting to Figure 24, in comparison with Figure 8, it will be noted that two sleeves 21 are secured to the shaft 14 and are located on opposite sides of the rotatable sleeve 19. The sleeves 21 have outwardly projecting radial guides 22 in which plungers 23 can slide, parallel to the shaft 14. The plungers 23 are supplied at their inner ends with heads 24 which, as shown in Figure 3, are located at the inner or rear end of the conveyor 16. The plungers 23 carry angular brackets 25, the ends of which slide in the innermost guides 22. The plungers 23 and the print-gripping heads 24 are pressed toward the longitudinal center of the frame 1 by springs 26. The brackets 25 cooperate with ratchets 20 on the ends of the sleeve 19.

Operation of the print feed.—The motor 2 is put into operation by means of the switch 3 and rotates the shaft 5, the worm 7 and the worm wheel 8 rotating the shaft 9, and the crank 10 actuating the connecting rod 11, oscillatory motion being imparted to the shaft 14 by way of the crank arm 12. When the shaft 14 is rocked, the sleeves 21 are rocked also. When the sleeves 21 are turned clockwise in Figures 24 and 3, through an arc of about ninety degrees, the brackets 25 cooperate with the ratchets 20 to turn the sleeve 19, the sprocket wheel 15 actuating the conveyor 16 and causing the prints of butter to be moved to the right in Figure 3 or to the left in Figure 4. During this movement, the innermost print of butter, marked by the numeral 44 in Figure 4 is gripped at its ends by the heads 24. The print 44 of Figure 4 is carried down, by the heads 24, underneath a vertically movable ram 27, to be alluded to hereinafter. By the time that the print of butter is well underneath the ram 27, the direction of oscillation of the crank 12 of Figure 3 is reversed, and the brackets 25 start to climb up the inclined surfaces of the ratchets 20.

When the brackets 25 climb up the inclined surfaces of the ratchets 20, during the counterclockwise rotation of the shaft 14 and the

sleeves 21, the sleeve 19 and the conveyor 16 remain at rest, the plungers 23 moving to the left in Figure 24, and the heads 24 being released from the ends of the print of butter that is under the ram 27. Ultimately, the guides 22 assume the vertical position of Figure 3, the brackets 25 snapping into engagement with the depressions of the ratchets 20, under the action of the springs 26. The heads 24 have now gripped another print of butter at its ends, on the conveyor 16, and the parts are set to rotate the sleeve 19 clockwise in Figures 24 and 3, so as to bring the print down under the ram 27, as has been mentioned hereinbefore.

The ram.—The ram 27 (Figures 8 and 4) is in the form of a block, attached to a skeleton slide 28 mounted for vertical reciprocation in guides 29 on the frame 1. The upper end of a pitman 30 is pivoted to the slide 28, the pitman extending downwardly at one side of the machine. The pitman 30 has a loop-shaped lower end 31 (Figure 3) receiving a shaft 32 (Figure 8) journaled in the frame 1. The shaft 32 serves as a means for guiding the vertical movement of the pitman 30, although the shaft has other important functions.

It appears from Figure 3 that the pitman 30 has an offset 33 at its lower end, and to this offset are pivoted links 34 which, in their turn, are pivoted to a crank 35 secured to a transverse shaft 36 (Figure 5) supported for rocking movement on the frame 1. An arm 37 is secured to the shaft 36 and carries a counter-weight 38. A rearwardly extended arm 39 is secured to the shaft 36, the arm 39 being pivoted to a link 40 (Figure 4) connected by a pull spring 41 to the casing 6. The link 40 is pivoted to a slide rod 42 mounted to reciprocate horizontally in the casing 6 and provided with a roller (not shown) that bears against a cam 43 (Figure 8) on the shaft 9.

Operation of the ram.—The ram 27 moves vertically as the slide 28 reciprocates in the guides 29, the pitman 30 actuating the slide, and vertical motion being transmitted to the pitman from the shaft 36 by the arm 35 and the links 34 of Figure 3. The shaft 36 receives motion from the power driven shaft 9 of Figure 8 through a train of parts including the cam 43, the slide rod 42, the link 40, and the arm 39, on the shaft 36.

The paper feed.—Horizontal guides 45 (Figures 21, 2 and 6) are mounted on the frame 1. A bracket 46, which is U-shaped in plan, extends rearwardly from the guides 45. A slide 47 is mounted to reciprocate on the guides 45. Links 48 (Figure 4) are pivoted to the slide 47 and to arms 49 that extend upwardly from a transverse shaft 50 (Figure 6), the shaft having depending arms 51 to which is pivoted a pitman 52 (Figure 4) connected to a crank 53 on a shaft 54 (Figure

5) journaled on the frame 1. A sprocket wheel 55 is connected to one end of the shaft 54, externally of the frame of the machine, and cooperates with a sprocket chain 56 engaged about a sprocket wheel 57 (Figures 7, 1, and 8) secured to one end of the main shaft 9.

The slide 47 (Figure 21) has inwardly projecting arms 59 terminating in fixed jaws 58. Shafts 60 are mounted to rock in the slide 47 and in the arms 59. At their forward ends, the shafts 60 carry movable jaws 61 (Figure 22) that cooperate with the jaws 58 in gripping the piece of paper 89 which is to be wrapped about the block of butter.

The shafts 60 are provided at their rear ends with cranks 62 (Figure 2) to which are pivoted inwardly extended pitmen 63 (Figures 21 and 22), the inner ends of the pitmen being pivoted to a crank disc 64 on a shaft 65 rotatable in a bearing 66 carried by the slide 47. The shaft 65 can rotate and slide longitudinally in a bearing 67 on the bracket 46 which forms part of the fixed frame work of the machine. A spring 68 (Figure 22) is secured to the crank disc 64 and to the slide 47. When the spring 68 is inclined to the left, as in Figure 22, the spring tends to hold the jaw 61 closed with respect to the jaw 58 on the paper 89, but when the crank disc 64 is rotated far enough in the direction of the arrow in Figure 22, then the spring 68 will incline to the right hand side of the center of rotation of the disc 64 and tend to hold the jaw 61 in open position with respect to the jaw 58 and the paper 89. A cam 69 (Figures 21 and 1) is mounted on the rear end of the shaft 65, and a cam 70 is mounted on the forward portion of the shaft, the cams being held in place by set screws 90 on the shaft 65 for circumferential adjustment. The cams 69 and 70 cooperate, one at a time, with the bearing 67 of Figure 21, to rotate the shaft 65, in a way which will be described hereinafter.

Supports 71 (Figures 1 and 2) are mounted on the rear end of the frame 1 and carry a roll 72 of paper, whereof the piece shown at 89 in Figure 22 is a part. An upwardly and forwardly extended table 73 is mounted on the rear end of the frame 1 and carries a paper guide 74 which need not be described in detail, because it may be of any appropriate construction. The paper, proceeding to the paper guide 74 from the roll 72, passes under a roller 91 journaled on the supports 71.

Operation of the paper feed.—Suppose that the paper has been pulled forward as shown in Figure 2, and as indicated in Figure 25, so that the paper is underneath the print of butter that is to be forced down by the ram 27. Under such circumstances, the jaws 61 grip the paper 89, as shown in Figure 22, under the action of the spring 68. A length of paper is cut off, by a means to

be described hereinafter, as the slide 47 arrives at the extreme right hand end of its travel. As the slide 47 arrives at the extreme right hand end of its travel, in Figure 5 1, the cam 69 cooperates with the bearing 67 to rotate the shaft 65.

When the shaft 65 is rotated as aforesaid, the disc 64 and the pitmen 63 operate through the crank arms 62 to rock the shafts 10 60 and to cause the jaws 61 to release their hold on the piece of severed paper which is to be wrapped around the butter. By the operation last-mentioned, the pull spring 68 of Figure 22 is swung to the right of the 15 center of rotation of the crank disc 64, and holds the jaws 61 open. With the jaws 61 opened, the slide 47 is moved to the left in Figure 21, and the jaws 61 and 58 are disposed respectively below and above the end 20 of the piece of paper that has not yet been cut off from the roll 72, or been advanced into the position shown in Figure 21. When the slide 47 moves far enough in Figure 21, so that the cam 70 cooperates with the bearing 25 67, the shaft 65 is rotated, and the jaws 61 are closed on the paper, the spring 68 returning to the position of Figure 22, to hold the jaws 61 in engagement with the paper. The slide 47 then is carried to the right in 30 Figure 21, and the operation is repeated, length after length of paper being unreeled from the roll 72, and cut off, as the ram 27 shoves down piece after piece of butter, for wrapping.

35 The slide 47 is reciprocated by a train of parts including the shaft 9, the sprocket wheel 57 (Figure 1), the chain 56, the sprocket wheel 55, the shaft 54, the crank 53, the pitman 52 (Figure 5), the arms 51 (Figure 6), the shaft 50, the arms 49 (Figures 1 and 6), and the links 48.

40 *The cutting mechanism.*—The wrapping paper is advanced across a fixed blade 75 (Figure 4) supported by the frame. A movable shear 76 (Figure 7) cooperates with the fixed blade 75 to cut off a length of the wrapping paper. The movable shear 76 is fulcrumed at 77 on a bracket 78 of L-shape carried by one side of the frame 1. A connecting rod 79, shown to good advantage in Figures 7 and 8, is pivoted at its upper end to the intermediate portion of the shear 76. The rod 79 is raised, and the shear 76 elevated, by a strong compression spring 80 connected to the horizontal part of the bracket 78 (Figure 7) and to the rod 79. Upward movement of the shear 76 is limited by the engagement shown at 82 in Figure 7 between the shear and the vertical part of the bracket 55 78.

50 The lower end of the rod 79 is pivoted to an arm 81 (Figure 3) on a shaft 82 (Figure 5) mounted to rock in the frame 1 and offset at 83 to clear the motor shaft 5. The shaft 82 has an arm 84 (Figure 4) to which is piv-

oted a link 85 that is pivoted to a slide rod 86 mounted to reciprocate in the casing 6, the rod 86 carrying a roller 87 which cooperates with a cam 88 on the main shaft 9.

55 *Operation of the cutting mechanism.*—The shear 76 is raised and lowered with respect to the fixed blade 75, to cut off a piece of wrapping paper of the desired length, by a train of parts including the main shaft 9 (Figure 8), the cam 88 (Figure 4), the link 85, the arm 84, the shaft 82 (Figure 5), the arm 81, and the connecting rod 79 of Figures 3 and 7. The weight of the shear 76 and attendant parts aids in bringing about the downward movement of the shear, the spring 80 assisting in elevating the shear.

60 *The rotor or print carrier.*—The rotor or print carrier 93 is shown in its place in the machine in Figure 4, and appears in many other figures of the drawings, for instance, Figures 18, 20, and 8. The rotor 93 is secured to the shaft 32 and turns therewith. The rotor 93 has longitudinal seats 94. These seats 94 pass, one after another, under the vertically movable ram 27 (Figure 9), and a means is provided for steadyng the rotor 93, so that one of the seats 94 will be directly under the ram 27, to receive the print of butter and the piece of paper. The means above referred to is shown in detail in Figure 23, and embodies bearings 95 (Figure 4) on the casing 6. A shaft 96 is mounted to rock in the bearings 95 and carries arms 97 in which a stop roller 99 is journaled. A retractile spring 98 is connected to one of the arms 97 and to the casing 6, the spring keeping the roller in frictional contact with the periphery of the rotor 93.

65 A ratchet wheel 100 (Figures 3 and 2) is secured to the shaft 32. A pawl 101 cooperates with the ratchet wheel 100 and is carried by a wheel 102 rotatable on the shaft 32. A connecting rod 103 is pivoted to the wheel 102 and to the crank 10 (Figure 8) on one end of the main shaft 9.

70 *Operation of the rotor.*—The roller 99 (Figure 23) engages in one of the seats 94 of the rotor 93 to hold another of the seats 94 directly under the ram 27 of Figures 9 and 7. When the ram 27 comes down, it carries the print 104 of butter into the uppermost seat 94 of the rotor 93 with the severed sheet 105 of paper around the print, as shown in Figure 26. The rotor 93 is turned, a quarter of a revolution at a time, by the shaft 32, the ratchet wheel 100 that is fixed to the shaft 32, the pawl 101 on the wheel 102 that turns on the shaft 32, the connecting rod 103, and the crank 10 on the shaft 9.

75 *Structure and operation of the folding mechanism.*—Up to this point in the description, the print 104 of butter is in one of the seats 94 of the rotor 93, the sheet 105 of paper being disposed about the print, in U-shape, as shown in Figure 26. Referring to

Figures 11 and 10, the first step in the folding operation is to turn over one end 106 of the sheet of paper on top of the print 104.

The fold at 106 is made by a roller 107 which has limited movement on the periphery of the rotor 93 (compare Figures 10 and 12). The roller 107 is journaled in a yoke 108 which is pivoted to a slide or rod 109, mounted to reciprocate in a guide (Figure 1) 110 supported on the main frame 1 of the machine. The slide 109 is pivoted to a link 111 which, in its turn, is pivoted to an up-standing arm 112, on a sleeve 114 (Figure 5), the sleeve being mounted to rock on the shaft 36. The shaft-carried sleeve 114 has a depending arm 115 (Figure 1) pivoted to a link 116, the link being pivoted to a slide rod 117 mounted to reciprocate in the casing 6. A pull spring 118 is connected to the link 116 and to the casing 6. On the inner end of the slide rod 117 is a roller like the roller 87 of Figure 4, that cooperates with a cam 119 (Figures 4 and 8) on the shaft 9.

When the roller 107 is advanced as in Figure 10, it forms the fold 106 of Figure 11, the roller 107 being operated by the yoke 108, the slide 109, the link 111, the arm 112, the sleeve 114, the arm 115, the link 116, the slide rod 117, and the cam 119 on the main shaft 9.

After the fold at 106 has been made, the next operation is to turn up the first end flaps 126 of Figure 13. The mechanism for doing this comprises plungers 128 (Figures 8 and 12) that reciprocate vertically in guides 129 on the frame work of the machine. The lower ends of the plungers 128 are pivoted to slide rods 130 that move vertically in the casing 6, the rods 130 carrying rollers 131 cooperating with cams 132 on the main shaft 9. The upper ends of the plungers 128 are offset inwardly (Figure 12). On the upper ends of the plungers 128, levers 133 are fulcrumed intermediate their ends, as shown in Figure 8. On the outer ends of the levers 133, rollers 127 are journaled, rollers 134 being journaled on the inner ends of the levers 133. The rotor 93 is hollow, so that there are circular tracks 135 (Figures 20, 8 and 12) in the ends of it. Pull springs 136 (Figure 8) are secured to the guides 129 and to the outer ends of the levers 133.

The springs 136 tend to keep the rollers 134 in engagement with the tracks 135 of the rotor 93. When the plungers 128 are raised by the cams 132, the rollers 131, and the slide rods 130, the rollers 134 act as fulcra for the levers 133, and swing the levers, so that the rollers 127 are carried inwardly and upwardly along the ends of the paper on the print 104 to form the first end flaps 126 of Figures 13 and 12. When the shaft 9 turns the cams 132 to the proper position, the plungers 128 move downwardly, and the

springs 136 restore the levers 133 and the rollers 127 to the position of Figure 8.

The next operation is to turn in the second end flaps 137 of Figures 15 and 14. For the doing of this, there is provided a mechanism including slides 139 (Figures 4, 8 and 16) which have right line reciprocation in guides 138 on the framework of the machine. Arms 140 are pivoted to the slides 139 and carry rollers 141 which turn on vertical axes. Torsion springs 142, engaged with the arms 140 and with the pivot elements that attach the arms to the slides 139, cause the arms 140 to swing inwardly, thereby holding the rollers 141 yieldably against the ends of the rotor 93, as shown in Figures 12 and 8.

Angular links 143 (Figures 4 and 14) are pivoted to arms 144 on sleeves 145 (Figure 8) mounted to rock on stub shafts 146 carried by the frame 1. The sleeves 145 have depending arms 147 which are pivoted to links 148, the lower ends of the links being pivoted to slides 149 carrying rollers 150 that cooperate with cams 152 on the main shaft 9.

When the shaft 9 operates the cams 152, the slides 149 and the links 148 move upwardly, the sleeves 145 being rocked through the instrumentality of the arms 147 on the sleeves, the arms 144 on the sleeves moving the slides 149 to the left in Figure 14, the rollers 141 turning over the second end flaps 137. The retraction of the rollers 141 from the position of Figure 14, after the flaps 137 have been made, need not be gone into, because it is controlled by the cams 152 of Figure 8, in a way readily understood by anyone familiar with the function of a cam.

By the time that the wrapping operation has reached the point shown in Figures 14 and 15, one end 106 of the piece of paper has been turned down. The opposite end 153 of the piece of paper is still sticking up. The means for folding down the end 153 of the piece of paper is simple. It embodies a roller 154 (Figure 2) extended cross-wise of the machine and journaled on levers 155 mounted to swing on the frame and pulled down by springs 156 (Figure 1) attached to the said levers and to the frame work, the construction being such that the roller 154 rolls on the rotor 93. The rotor 93, as it turns, carries the end 153 of the paper under the roller 154. The end 153 of the paper is shown partly flattened down in Figures 16 and 17, but by the time that the rotor has turned clockwise through an arc of ninety degrees, from the position of Figure 14 to the position of Figure 18, the end 153 of the paper is folded down closely on the end 106.

Third end flaps 157 exist in the wrapping paper and the flaps 157 must be turned down from the position of Figure 17 to the position of Figure 19, this operation taking place whilst the rotor 93 is rotating counterclockwise from the position of Figure 14 to the

position of Figures 18. The mechanism for turning over the third end flaps 157 preferably embodies a support in the form of a transverse bar 158 (Figure 7) mounted on the framework 1. Levers 159 are fulcrumed on the support 158 and carry rollers 161 constrained to bear against the ends of the rotor 93 by a pull spring 160 which connects the levers 159. As the rotor 93 moves from the position of Figure 14 to the position of Figure 18, the outstanding flaps 157 of Figure 17 pass under the rollers 161 and are folded down tightly as shown in Figure 19. There now exists a fourth end flap 162 to be bent over, but the bending over of this flap will be considered in connection with the operation of the ejector mechanism.

The ejector mechanism.—In describing the ejector mechanism, attention is called to the fact that, in Figure 8, the main shaft 9, is shown as provided with a cam 163 which operates a slide rod 164 (Figure 3) mounted to reciprocate horizontally in the casing 6 and pivoted to a link 165, the link being pivoted to an arm 166 on a sleeve 167 (Figure 5) mounted to rock on the shaft 83. The sleeve 167 has an upstanding arm 168 (Figure 4), and a pull spring 171 connects the said arm with the rear portion of the frame 1, as Figure 2 discloses. A link 169 is pivoted to the arm 168 and is pivoted to a horizontally movable bell crank lever 170 (Figure 5) fulcrumed on the frame. The long arm of the bell crank lever 170 is pivotally connected at 172 with an L-shaped slide 173 (Figures 14 and 4) that moves crosswise of the machine on a track 176, which may be a channel bar to be seen in side elevation in Figure 7, and in end elevation in Figure 1. An inner shoe 174 (Figures 7, 16 and 5) is secured to the slide 173 and reciprocates within the track 176. Outer rollers 175 are journaled on the slide 173 and engage the track 176 externally (Figures 5 and 18). The ejector (Figures 12, 1, and 20) is marked by the numeral 177, and may be a block, attached to the slide 173. The ejector 177 is so located that it will shove the partly wrapped print 120 of Figure 20 lengthwise of the seat 94 in the rotor 93, and into a chute 178 carried by the frame. One of the fourth end flaps 162 is turned over by contact with the ejector 177 and the other of the fourth end flaps is turned over by contact with a preceding print that has been transferred to the chute 178, and by the time that the print is in the chute 178, both of the flaps 162 have been folded against the ends of the print, approximately as shown at 180, the completely wrapped print being marked by the numeral 179 in Figure 20.

As to the final folding of the wrapper, at the ends, the final folds are completed when the butter is placed in the carton. Even though the ejector does not effect a perfect

final fold, there is, nevertheless, a definitely folding, in that the paper at the ends of the piece of butter is mashed down. The butter is completely covered, in any event, and the butter is protected and kept clean. If the operator desires a symmetrical and perfect final fold, he can make it when placing the butter in the carton, but the article, as it comes from the machine, is completely wrapped, in the sense that it is completely covered by the paper, even though the final fold may not assume the perfection and symmetry of the folds 137 and 157, for instance, in Fig. 19 of the drawings.

Operation of the ejector.—The ejector 177 is operated by a train of parts including the cam 163, the slide rod 164, the link 165, the arm 166, the sleeve 167, the arm 168, the link 169, the bell crank 170, and the slide 173 which is held by the shoe 174 and the rollers 175 for reciprocation on the track 176.

The delivery conveyor.—As the completely wrapped print 179, of Figure 20, moves out of the chute 178, the print passes upon an endless delivery carrier 181 (Figures 1, 8, and 2) that extends backwardly toward the rear end of the machine. The conveyor 181 is carried by an idle drum 182 journaled on a stub shaft 189 carried by the frame. The endless conveyor 181 cooperates with a power driven drum 183 mounted to turn on a shaft 184 on the frame. A radius arm 185 (Figure 1) swings on the shaft 84 and bears a spring actuated pawl 186 cooperating with a ratchet wheel 187 (Figure 2) on the inner end of the drum 183. A pitman 188 is pivoted to the sprocket wheel 57 and to the outer end of the radius arm 185.

Operation of the delivery conveyor.—When the wrapped print of butter passes upon the conveyor 181, the print is moved away from the chute 178 of Figure 2 toward the rear end of the machine. The conveyor 181 is driven by the shaft 9, the wheel 57, the pitman 188, the pawl 186, the ratchet wheel 187, and the drum 183.

General operation.—The statement of operation may be abbreviated to a résumé in view of what has been stated hereinbefore in connection with the working of the several constituent mechanisms.

The conveyor 16 of Figure 4 carries the prints into the machine. The innermost print 44 of Figure 4 is held by the grips 24 of Figure 8 whilst the said print is being carried downwardly under the ram 27. The grips or jaws 58-61 of Figure 21 carry the paper under the print, and a length of paper is cut off by the shear 76. The ram 27 moves the print and the paper into the uppermost seat 94 of the rotor 93 (Figure 26). The roller 107 of Figure 10 advances and makes the fold 106 of Figure 11. The rollers 127 of Figure 12 rise and fashion the flap 126. The rollers 141 move to the left into the position of Fig-

ure 14 and turn over the second end flap 137. The rotor 93 turns, and the end 153 of the wrapping paper is flattened down by the roller 154. As the rotor turns, it carries the print past the rollers 161, and the third end flaps 157 are turned over.

The ejector 177 takes the print 120 of Figure 20 out of the rotor 93, the fourth end flaps 162 being closed down, and the print 10 being advanced into the position shown at 179 in Figure 20. As one print passes into the chute 178, it crowds out a preceding print upon the conveyor 181 of Figure 2, and the conveyor moves the wrapped print along 15 toward the rear end B of the machine.

Having thus described the invention, what is claimed is:

1. In a wrapping device, a movable carrier for the article to be wrapped, a movably mounted ram, means for moving the ram toward and away from the carrier, an endless conveyor constituting means for moving the article to be wrapped toward the ram and into position between the ram and the carrier, a shaft mounted for rotary oscillation, means for imparting rotary oscillation to the shaft, an automatically releasable clutch connection between the shaft and the conveyor and imparting step by step advancement to the conveyor, a grip mounted on the shaft and releasably engaging the article to be wrapped whilst the conveyor is moving the article into position between the ram and the carrier, the clutch and the grip embodying enterengaging parts which advance and retract the grip as the shaft is oscillated, and means for interposing a wrapper between the article to be wrapped and the carrier.

2. In a wrapping device, a rotatable carrier for the article to be wrapped, the carrier having a circumferential track, a plunger mounted for straight-line sliding movement, a lever pivotally mounted intermediate its ends on the plunger, one end of the lever cooperating with the track, a folder at the opposite end of the lever, and means for imparting movement to the plunger to cause the lever to tilt with the track as a fulcrum, and bring the folder into operative relation to the end of the carrier.

3. In a wrapping machine, a shaft supported for rotation, a sleeve rotatable on the shaft, an endless conveyor driven by the 55 sleeve, a ratchet on the end of the sleeve, a grip so placed as to engage an article on the conveyor, the grip being slidable longitudinally of the shaft and including a part engaged with the ratchet, a movable carrier, a folding mechanism cooperating with the carrier, yieldable means for advancing the grip to cause the grip to engage an article on the conveyor, means for rotating the shaft in one direction to cause said part of the grip to 65 cooperate with the ratchet in turning the

sleeve, advancing the conveyor, and causing the grip to move the article to a position for discharge upon the carrier, and means for rotating the shaft in an opposite direction to cause said part of the grip to slide over the ratchet and retract the grip for engagement with another article on the conveyor under the impulse of said yieldable means.

4. In a wrapping device, a movable carrier for the article to be wrapped, means for wrapping the article in the carrier, an ejector, means for moving the carrier to bring the article into the path of the ejector, and mechanism for operating the ejector, said mechanism comprising a fixed track, a slide 75 mounted to reciprocate on the track and supporting the ejector, a bell crank lever and a fulcrum therefor, one arm of the bell crank lever being pivotally connected to the slide, a first shaft supported for rocking movement and having arms, a connection between one arm of the first shaft and the other arm of the bell crank lever, a second shaft supported for rotation, means for rotating the second shaft, and means for connecting 80 the second shaft operatively with the other arm of the first shaft.

5. In a wrapping device, a rotatable carrier for the article to be wrapped, a freely rotatable folder rotatable by contact with 95 the end of the carrier and movable upon the end of the carrier in a direction substantially at right angles to its axis of rotation, means for moving the folder in a direction substantially at right angles to its axis of 100 rotation, upon the end of the carrier, a freely rotatable folder cooperating with the end of the carrier, and means for rotating the carrier with respect to the last-specified folder, thereby to render the last-specified folder 105 active, and to cause it to rotate.

6. In a wrapping device, a rotatable carrier for the article to be wrapped, a slide mounted for straight-line movement at the end of the carrier in a direction transverse 110 to the axis of rotation of the carrier, means for reciprocating the slide in the direction of its length, an arm pivoted to the slide, a roller journaled on the arm, and spring means for actuating the arm to cause the roller to 115 bear on the end of the carrier.

7. In a wrapping device, a frame, a rotatable carrier for the article to be wrapped, and journaled on the frame to turn about an axis, levers fulcrumed at their outer ends 120 on the frame to swing parallel to said axis, folders carried by the inner ends of the levers and located at opposite ends of the carrier, and a pull spring joining the levers intermediate their ends and constituting means for 125 maintaining the folders engaged with the ends of the carrier, with an equalized pressure.

8. In a wrapping machine, a frame, a rotatable carrier journaled on the frame, a 130

fixed track extended across the frame from side to side in parallel relation to the carrier, and across the carrier from one end of the carrier to another, a slide mounted to reciprocate longitudinally of the track and including a ram movable longitudinally of the carrier, a long lever fulcrumed at a point remote from the slide, the lever being mounted to swing in a substantially horizontal plane, parallel to the track, and means for pivotally connecting the lever at one end to the slide, the track supporting said end of the lever and supporting the slide at any point between the ends of the carrier where the ram is operating.

9. In a wrapping device, a rotatable carrier having circumferentially spaced seats for an article to be wrapped, mechanism for depositing a wrapper and an article to be wrapped in one of said seats, means for folding the wrapper about the article in the seat, and means yieldably engaged directly with the carrier, and movable to engage directly in another of said seats for an article, to hold the carrier against rotation and to position the first-specified seat for cooperation with said mechanism.

In testimony that I claim the foregoing as my own, I have hereunto set my hand.

EVERETT E. EPLING.
